UNITED STATES PATENT OFFICE.

ROBERT M. PRINGLE, OF ST. LOUIS, MISSOURI, ASSIGNOR TO COREY ESTATE COMPANY, OF ST. LOUIS, MISSOURI, A CORPORATION OF MISSOURI.

FIRE-HYDRANT.

No. 821,191.

Specification of Letters Patent.

Patented May 22, 1906.

Application filed July 10, 1905. Serial No. 269,045.

To all whom it may concern:

Be it known that I, ROBERT M. PRINGLE, a citizen of the United States, residing at St. Louis, Missouri, have invented a certain new and useful Improvement in Fire-Hydrants, of which the following is a full, clear, and exact description, such as will enable others skilled in the art to which it appertains to make and use the same, reference being had to the accompanying drawings, forming part of this specification, in which—

Figure 1 is a vertical sectional view of my improved fire-hydrant. Fig. 2 is a similar view showing the main valve open. Fig. 3 is an enlarged vertical sectional view on line 3 3, Fig. 1, showing the drain-valve. Fig. 4 is a sectional view on line 4 4, Fig. 3. Fig. 5 is a detail view of the drain-valve yoke. Fig. 6 is a detail view of the bearing-block on the lower end of the valve-operating rod, and Fig. 7 is a detail view of the socket-piece in which the valve-operating rod is mounted.

This invention relates to a new and useful improvement in fire-hydrants, and particularly to the operating mechanism of the main valve and the drain-valve.

The objects of the present invention are to construct the device so that the main and drain valves can be inserted and removed through the top of the stand-pipe without taking said stand-pipe from the ground and to simplify the construction and reduce the number of parts, so that there is little liability of said parts getting out of order.

With these objects in view the invention consists in the novel construction, arrangement, and combination of the several parts, all as will hereinafter be described, and pointed out in the claims.

In the drawings, 1 indicates the stand-pipe, which may be of usual construction, the upper portion of which is designed to stand above the ground, while the lower barrel or portion of which is designed to be buried in the ground below the frost-line.

2 is a threaded boss on the exposed portion of the stand-pipe for the attachment of fire-hose.

3 is a valve-operating rod which extends through the cap-piece of the stand-pipe and is made non-circular in cross-section, where-

by said rod may be rotated on the application of power thereto through the medium of a wrench. This rod extends down into the stand-pipe and is preferably connected to, 55 although it may be a part of, the threaded portion 4 of the valve-operating rod. The lower end of rod 3 is provided with a bearing-block 5, (see Fig. 6,) whose lower face is preferably conical in shape, so as to center the 60 valve-operating rod in its socket-bearing and reduce the frictional resistance.

6 indicates the socket-piece arranged in the lower end of the valve-operating rod, said socket-piece fitting within the upper end of 65 the barrel 7, containing the drain-valve hereinafter described. This barrel 7, as shown in Fig. 3, is secured in position in the bottom of the stand-pipe and the cap-piece 6 loosely fitted in the upper end thereof, said cap-piece, 70 however, having a rearward extension fitting against the back wall of the stand-pipe, whereby said cap-piece is prevented from turning.

The valve-operating rod is provided with 75 three threaded portions, two of which are similarly pitched, but in opposite directions, these being useful in manipulating the main valve, while the third threaded portion is of less pitch and is located near the lower extremity of the valve-operating rod, this third threaded portion being useful for operating the drain-valve. For convenience I will designate the threaded portions of the rod above referred to as *a*, *b*, and *c*, respectively. 80 85

8 indicates nuts which are mounted on the threaded portions *a* and *b* of the valve-operating rod, said nuts having rearward extensions to coöperate with the back wall of the stand-pipe, so as to take the strain transmitted to said nuts when the valve is seated from the valve-operating rod. The opposite sides of nuts 8 are provided with lugs or ears to which are pivotally connected links 9, the opposite ends of said links being pivotally connected to the main valve 10. Valve 10 co-operates with a valve-seat arranged in the stand-pipe, said valve when closed closing communication between the water-main and the stand-pipe, as shown in Fig. 1. When 100 the valve is open, as shown in Fig. 2, water may enter the stand-pipe from the main.

Links 9 are connected together on opposite sides of the pivotal points of their connection to the main valve by a link 11, the function of which link 11 is to maintain the main 5 valve in its vertical position during its movement to and from its seat. Link 11 thus dispenses with guideways in the side walls of the stand-pipe, which have heretofore been used for maintaining the main valve in vertical 10 position in one form of hydrants with which I am familiar, and said link also dispenses with a plurality of links connected at different points to the nuts and to the main valve—say, for instance, four links—in another form of valve with which I am familiar. 15

In operation it is only necessary to rotate the rod 3, say, to the right when the parts are in the position shown in Fig. 1, and the main valve will be moved to the position shown in 20 Fig. 2 and establish communication between the main and stand-pipe. To close the main valve, it is only necessary to rotate the valve-operating rod 3 in the opposite direction, or to the left. The rotation of the operating- 25 rod to open and close the main valve also effects the closing and opening of the drain-valve, as follows: 12 indicates a yoke whose upper portion is threaded so as to coöperate with the threaded portion *c* of the valve-operating rod. The side members of this yoke extend down on each side of the socket-bearing 30 6, which is cut away to receive the said yoke members, as shown in Fig. 7, the yoke members being connected at their lower ends, as shown in Fig. 3, and having a threaded extension on which the drain-valve 13 is secured. This drain-valve may be made of 35 rubber or other suitable material and cup-shaped, if desired, as is well known. The barrel 7, in which the drain-valve operates, is preferably formed with a bore of uniform 40 diameter throughout its length, into the upper end of which are seated the depending flanges of the socket-piece 6, the laterally-extending flanges of said socket-piece extending 45 over the edges of the barrel, so as to afford a firm support for the valve-operating rod. Drain-openings 14 lead from the interior of the stand-pipe into the upper portion of the 50 barrel 7, as shown.

15 indicates an annular groove formed in the bore of the barrel 7, beneath which groove are formed longitudinally-disposed channels 16.

55 In assembling the parts the yoke of the drain-valve is first screwed onto the valve-operating rod, after which the cap-piece is slipped into the yoke and the bearing-block on the end of the valve-operating rod introduced 60 into its receiving-socket. The valve-operating rod, with its main valve and drain-valve in the position shown in Fig. 2, may then be introduced into the stand-pipe, the drain-valve being inserted into its barrel and

the cap-piece adjusted upon the upper end of 65 the barrel, when the parts are ready for operation, the cap of the stand-pipe being of course secured in position. When the main valve is forced to its seat, the drain-valve descends to the position shown in Figs. 1 and 3— 70 to wit, below the groove 15—so that any water remaining in the stand-pipe may escape through the openings 14 into the barrel of the drain-valve and from said barrel through the grooves 15 and 16 to the exterior. When the main valve is opened and the water enters the stand-pipe from the main, the drain-valve 13 is caused to rise above the groove 14, as 75 shown in Fig. 2, and shut off communication between the drain-openings of the stand-pipe and the exterior.

I am aware that minor changes in the construction, combination, and arrangement of the several parts of my hydrant may be made and substituted for those herein shown and described without in the least departing from the nature and principle of my invention. 85

Having thus described my invention, what I claim, and desire to secure by Letters Patent, is—

1. In a fire-hydrant, the combination with a stand-pipe and its valve-seat, of a main valve, a valve-operating rod provided with oppositely-pitched threaded portions, nuts coöperating with said threaded portions, links 95 pivotally connected to said nuts and to said main valve, and an independent connection between said links whereby said links are caused to approach each other to nearly parallelism, when the main valve is seated; substantially as described.

2. In a fire-hydrant, the combination with a stand-pipe and its valve-seat, of a main valve, a valve-operating rod provided with oppositely-pitched threaded portions, nuts 105 coöperating with said threaded portions, links pivotally connected to said nuts and to said main valve, and a link 11 pivotally connected to said first-mentioned links on opposite sides of the pivotal points of connection of said 110 first-mentioned links to the main valve; substantially as described.

3. In a main-valve-operating mechanism for fire-hydrants, the combination with a valve-operating rod provided with two oppositely-pitched threaded portions, of a nut on each of said threaded portions, a main valve, a link extending from each nut and pivotally connected thereto and to the main valve, and a link coöperating with said links for maintaining the main valve in a vertical plane in its different adjusted positions; substantially as described.

4. In a fire-hydrant, the combination with a stand-pipe and its valve-seat, of a main 115 valve, a valve-operating rod, a barrel for a drain-valve arranged in the lower portion of the stand-pipe, said barrel having interior lon-

itudinally-disposed grooves in one of its ends, and a drain-valve connected to and operated by said operating-rod, said drain-valve in its movement passing the inner termi-
5 nes of said grooves; substantially as described.

In testimony whereof I hereunto affix my

signature, in the presence of two witnesses,
this 5th day of July, 1905.

ROBERT M. PRINGLE.
